UNITED STATES PATENT OFFICE.

HERMANUS A. HANSEN, OF SAN FRANCISCO, CALIFORNIA.

SCREEN DOOR.

Application filed May 31, 1917. Serial No. 195,413.

My invention relates to improvements in screen doors and the like wherein a movable panel is arranged to be moved to cover or uncover a screened opening to obtain an open screen or solid door as desired.

The primary object is to provide an improved door having a screen portion which may be covered or uncovered as desired.

Another object is to provide an improved door which may be easily converted from an open screen to a closed panel door to suit varying weather conditions.

A further object is to provide an improved door whereby a screen portion may be covered and effectively protected from exposure to the elements during winter seasons.

Another object is to provide an improved device of the character described wherein a movable panel is arranged to be moved to screen closing position and to form a tight and efficient closure.

A still further object is to provide an improved door wherein an adjustable panel is arranged to be secured to uncover a desired portion of a screened opening formed in the door.

I accomplish these and other objects by means of the improved device disclosed in the drawings forming a part of the present application wherein like characters of reference are used to designate similar parts throughout the specification and drawings, and in which,

Fig. 1 is a front elevation of my improved door.

Fig. 2 is a broken vertical section drawn upon a larger scale with the movable panel in open position.

Fig. 3 is a view similar to Fig. 2 with the panel in closed position.

Referring to the drawings, the numeral 1 is used to designate in general the frame of a door provided with a solid panel portion 2 and an open portion 3 having a screen 4 secured thereacross. The screen 4 may be made to cover any desired length less than half of the length of the inside of the frame. The upper edge of the screen is preferably secured within a bead or moulding 6 having inclined sides and the lower edge of the screen is preferably secured upon a rod 7 extending across the frame 1.

A recess 8 is formed in the solid panel portion 2 of the door, said recess having inwardly inclined surfaces 9 formed adjacent

the top thereof. A movable panel 11 is slidably mounted within the recess 8, said panel having a slot 12 formed therein to divide the panel into spaced wall portions connected at their lower ends to a widened base portion 13, having inclined surfaces 14 arranged to conform to the inclined surfaces 9. The upper ends of the wall portions are inwardly beveled as at 16 to conform to the inclined sides of the head or moulding 6. The recess 8 and panel 11 are made of a depth such that when the panel is lowered to its lower extreme position, the upper edge of the panel will substantially match with the upper edge of the closed panel portion 2 of the door and when raised to its upper extreme position the inclined surfaces 14 will wedge against the surfaces 9 and the beveled surfaces 16 will wedge against the bead 6.

Pins 17 are secured upon the movable panel 11 and arranged to extend outwardly through slots 18 formed in the sides of the frame 1. Securing elements 19 are threaded or otherwise mounted upon the pins for detachably securing the panel in a desired position relative to the screened portion 2 of the door.

In operation, the door is mounted within a doorway in the ordinary manner. When it is desired to have an open screened door, the movable panel is lowered to its open position as shown in Figs. 1 and 2 of the drawings, thereby uncovering the screened opening 3 of the door. When it is desired to close the screened opening 3, the securing elements 19 are loosened and the panel raised upwardly to the position shown in Fig. 3 of the drawings, the inclined surfaces 14 and 16 being wedged against the adjacent portions of the door to obtain a tight closure as above explained. The securing elements 19 are then tightened to clamp the panel in closed position. If it is desired to only partially close the screened opening 3, the panel is raised to cover the desired portion of the opening and the securing elements 19 tightened to hold the panel in the desired adjusted position.

It will be noted that when the panel is moved to closed position, the screen 4 is fully enclosed between the spaced panel walls. Thus when the panel is closed during inclement weather, the screen is effectively protected from exposure to the elements, and the life of the screen will be

thereby greatly prolonged. This is particularly important in climates having long and snowy winter seasons where the exposure of the screen to snow and ice during the winter months is particularly destructive to screening such as commonly provided for screen doors. My present invention insures that the screen will be adequately protected and at the same time provides a double wall door construction affording a dead air space which forms an effective means for insulating against the passage of heat through the door and thereby results in a door which is warmer than the ordinary solid door construction. The screen is kept in position at all times and is available for use at any time by merely lowering the movable panel.

While I have illustrated and described only the preferred construction of my improved screen door, the device is of course subject to modification in various ways to suit various types of doors and various requirements. I, therefore, do not wish to restrict myself to the specific construction and arrangement disclosed, but desire to avail myself of all modifications which may fall within the scope of the appended claims.

Having thus described my invention, what I claim as new and desire to secure by Letters Patent is,

1. A screen door comprising a door frame having an open panel portion and provided with a closed panel portion having a recess formed therein; a screen mounted across the open panel portion; and a movable panel slidably mounted within the recess and slotted to form spaced walls arranged to be moved to cover both sides of the screen and close the open portion of the door, the screen being received in the slot and enclosed by the panel walls.

2. A screen door comprising a door frame having an open panel portion and provided with a closed panel portion having a recess formed therein; a screen mounted across the open panel portion; a movable panel slidably mounted within the recess and slotted to form spaced walls arranged to be moved to cover both sides of the screen and close the open portion of the door, the screen being received in the slot and enclosed by

the panel walls, and means for securing the movable panel in a desired position.

3. A screen door comprising a door frame having an open panel portion and provided with a closed panel portion having a recess formed therein; a screen mounted across the open panel portion; and a movable panel slidably mounted within the recess and slotted to form spaced walls arranged to be moved to cover both sides of the screen and close the open portion of the door, the screen being received in the slot and enclosed by the panel walls; and inclined surfaces formed upon the movable panel to wedge against adjacent portions of the door when the panel is in screen closing position to obtain a tight closure.

4. A screen door comprising a door frame having an open panel portion and provided with a closed panel portion having a recess formed therein; a screen mounted across the open panel portion; a movable panel slidably mounted within the recess and slotted to form spaced walls arranged to be moved to cover both sides of the screen and close the open portion of the door, the screen being received in the slot and enclosed by the panel walls; inclined surfaces formed upon the movable panel to wedge against adjacent portions of the door when the panel is in screen closing position to obtain a tight closure; and means for securing the movable panel in a desired position.

5. A screen door comprising a door frame having an open panel portion and provided with a closed panel portion having a recess formed therein; a screen mounted across the open panel portion; a movable panel slidably mounted within the recess and slotted to form spaced walls arranged to be moved to cover both sides of the screen and close the open portion of the door, the screen being received in the slot and enclosed by the panel walls; pins secured upon the movable panel and extending outwardly through slots formed in the door frame; and means engaging said pins for adjustably securing the panel in a desired position.

In witness whereof, I hereunto set my signature.

HERMANUS A. HANSEN.
